GOLF PUTTER HEAD

Raymond E. Carrier, 1017 N. Lake St.,
Burbank, Calif. 91502

Filed May 13, 1974, Ser. No. 469,224

Term of patent 14 years

Int. Cl. D21—02

U.S. Cl. D34—5 GH

FIG. 1 is a front view in perspective of a golf putter head embodying my new design;

FIG. 2 is a rear view in perspective thereof;

FIG. 3 is a front elevational view thereof;

FIG. 4 is a bottom plan view thereof;

FIG. 5 is a side elevation viewed from the right hand side of FIG. 3; and

FIG. 6 is a side elevation viewed from the left side of FIG. 3.

I claim:

The ornamental design for a golf putter head, substantially as shown.
